FLYERS FOR TEXTILE MACHINES

Arthur A. Brame, Greensboro, N.C., assignor to Brame
Textile Machine Company, Greensboro, N.C., a corpora-
tion of North Carolina

Filed Oct. 24, 1958, Ser. No. 769,340

5 Claims. (Cl. 57—115)

This invention pertains to flyers for textile equipment including roving frames and spinning frames in which the flyer has a matte-finished fiber contacting surface.

With the introduction of the man-made fibers and particularly nylon, Orlon, Dacron, among others, there is a tendency to build up a static charge while passing a sliver or roving over a surface which is conducive to storing an electrostatic charge and this is particularly evident in the roving made of synthetic fibers when the fibrous strand is passed through a flyer rove aperture or hole and into the hollow leg of the flyer frame. It is not unusual for fly and lint tag-ups to accumulate on the flyer which will ultimately result in neps and slubs. Also there is a tendency, due primarily to the accumulation of fly and lint, for a choke to form in the flyer hollow leg. By and large the textile industry has utilized highly polished fiber contacting surfaces which result in a high fiber-to-metal friction. These highly polished surfaces may be formed by nickel or chrome plating the fiber contacting surfaces particularly, chrome plating being preferred due to its increased wear resistance when subjected to the abrasive action of nylon and other synthetic fibers.

Therefore, it is one object of this invention to provide a flyer having a superficial matte-finish which will offer an appreciably reduced coefficient of friction between a roving and the metal contacting surface over which the roving comes in contact so as (a) to reduce fly and lint tag-ups, (b) eliminate appreciably fibers which choke up the flyer arm, (c) facilitate roving travel through the flyer by reduced drag through the flyer hollow leg, and (d) reduce the tendency of the surface fibers of the roving to be distorted and stretch the roving unintentionally.

Another objective of this invention is to present a method of applying a matte-finish to textile equipment and particularly to flyers for spinning and roving frames to achieve a greatly reduced fiber-to-metal frictional coefficient of drag.

Still another objective of this invention is to provide a novel fixture or rack assembly for use in the application of a chrome plate to the surface, internal and external, of a flyer and particularly to the hollow leg of the flyer frame.

A further objective of this invention is to provide a flyer in which the internal and external surfaces of which may be treated to form minutely indented surfaces as by sand-blasting or other means and by chrome plating the surface to form a semi-dull finish having a roughness rating and sheen which will account for a low friction between the fibers and metal which the fibers contact and extend the wear life of the flyer.

Yet another objective of this invention is the provision of a method of applying a matte chrome finish to a textile flyer apparatus which will have a surface roughness in the preferred range of 75 to 200 micro inches.

The present inventive concept contemplates the application of a matte-finished metal surface particularly applicable to various textile operations wherein man-made fibers, natural fibers, and their blends, including cotton and worsted spinning systems may utilize the resultant matte-finish to obtain lower fiber-to-metal friction compared to that normally obtained from the highly polished fiber contact surfaces conventionally used on textile ma-

2

chinery. The matte-finishes achieved are semi-dull in appearance and smooth to the touch as distinguished from a highly polished chrome finish or a dull finish which is undesirable.

Other objects and many of the attendant advantages of this invention will become more readily apparent to those conversant in this art as the same becomes better understood from the following detailed description taken in conjunction with the accompanying drawings in which like characters of reference refer to corresponding parts throughout the several views, and wherein:

FIG. 1 is a front elevational view of a flyer for textile machines with a transverse central sectional portion removed, illustrating, in outline form, a portion of the plating fixture in position;

FIG. 2 is an end elevational view of the flyer of FIG. 1;

FIG. 3 is a front elevational view of a plating rack assembly for supporting the flyer, shown in outline form, in a chrome bath for the application of a chrome plate on the flyer;

FIG. 4 is an end elevational view of FIG. 3;

FIG. 5 is a top plan view of the rack assembly of FIGS. 3 and 4;

FIG. 6 is a perspective view of one of the rack assembly clamping bars; and

FIG. 7 is an enlarged partial sectional view of the seating connection between the articulated rod for the hollow leg of a flyer.

Referring to the drawing and particularly to FIGS. 1 and 2, there is shown a flyer 10 of generally conventional structure in which the central socket portion 11 is provided with an axially extending bore 12 into which a roving is introduced generally at a suitable angle of introduction, so that the mouth 13 will impart a false twist to a bundle of fibers. The roving will be threaded through one of the rove exit openings 14 or 15 which may be in line with the entrance 16 to the hollow leg 17 or circumferentially spaced about the entrance socket such as the opening 16. The hollow leg 17 has an arcuate upper portion and a linear lower portion with an elongated slotted opening 18 therein and a shield 19 thereover. A presser foot 20 extends transversely from adjacent to the terminal end of the hollow leg and the presser foot is provided with a flat end 21 in which a roving guide opening 22 is placed therein. The presser foot will position the roving on a bobbin suitably mounted on the flyer frame or spinning frame to receive the yarn. The upper leg 23 of the presser foot encircles and is pivotally supported by means of the encircling lug 24 on the hollow leg above the projection 25. The lower end of the leg 23 is provided with a guide loop 30 to support the presser foot in alignment with the hollow leg.

A copper plug 26 having a T-handle 27 at one end and a slotted plug end 28 at the other end is shown inserted into the bottom open end of the axial bore 12. The balancing leg 29 is usually solid and extends in laterally spaced relation to the hollow leg and extends downwardly to form an inverted U-shaped flyer member.

In the preferred form of the present inventive concept, the flyer generally may be made of cold rolled steel and is assembled prior to any further mechanical working. Generally, after degreasing, cleaning and pickling, the entire assembly is sand-blasted, shot-blasted, or treated by some other known mechanism means for roughening or indenting the external and internal surfaces of the flyer, which roughness or indentation is not too apparent to the touch as the indentations are minute. It has been found most satisfactory to use a mixture of fine granules of sand, which granules are proportioned suitably in order to yield the requisite roughness which is determined primarily by the final surface conditions to be

attained by the particular roving material to be used in conjunction with the flyer. Particularly for the preparation of the internal surfaces of the socket and the hollow leg, a nozzle has been used at the end of the hose for projecting the particles of sand normal to the surface internally against which the particles impinge in order to obtain a suitable penetration or indentation of the surface.

Upon cleaning of the fine particles from the flyer surfaces, which particles usually cling to the internal and external surfaces of the flyer, the assembled unit is ready to be mounted on a rack assembly for supporting the flyer in an electrolytic bath for electroplating the exposed internal and external surfaces of the flyer with a chrome plate in one of the conventional plating procedures. After supporting the flyer on a suitable fixture, the assembly is normally cathode and the plate of chrome immersed in the electrolyte is the anode. When direct current is applied, the metallic ions migrate to the cathode or work and upon losing their charge, the metal is deposited on the cathode or work.

The normal practice of applying a chrome plate to a smooth surface results in a polished surface having a Profilometer reading R.M.S.: 10 micro inches and a coefficient of friction of 0.7. However, in the application of a matte-finish in accordance with this invention, a Profilometer reading of R.M.S.: 100 micro inches has been achieved with a resultant coefficient of friction of 0.14. It has also been determined that whereas the friction of polished surfaces varies greatly with the fiber speed, the friction of matte-finished surfaces is less affected by the variation in yarn speed. Actually the coefficient of friction between highly polished and matte-finished surfaces has been reduced from 0.7 to 0.14 by reducing the affected surface contact area. Measuring surface roughness may be performed by a commercial instrument known as a Profilometer manufactured by Micrometrical Manufacturing Company of Ann Arbor, Michigan, which instrument provides a sharp diamond stylus that moves over the surface to be measured at a constant rate and the rise and fall of this stylus is amplified electrically and indicated on a meter which is arranged to indicate directly the root-mean-square (R.M.S.) value of the surface measured.

In the matte-finish desirable for producing optimum results, the preferred range is from approximately Profilometer ratings of R.M.S.: 75 to 200, although some values of 40 to 75 may not be objectionable. A comparison with polished surface roughness indicates that polished surfaces range from R.M.S.: 0 to 20 micro inches.

There is illustrated in FIGS. 3, 4 and 5 a rack assembly or fixture 35 for supporting a flyer 10 for immersion into an electrolytic bath for chrome plating. The hook-end hanger rod 36 engages a horizontal tank bar 37 and extends vertically downwardly and has mounted adjacent to the terminal ends a pair of plastic clamping plates 38 of Plexiglas or similar material. A flyer supporting rod 39 is supported intermediate its ends between the clamping plates 38 and frictionally retained therebetween by the screws 40 in lateral parallel relation to the hanger rod. Clamping plates 41 are mounted at the lower terminal end 42 of the rod 39 to support the one end 43 of the hollow leg straight rod 44 which is introduced into the internal portion of the hollow leg 17 of the flyer.

Clamping plates 45 are supported above the plates 38 on the rod 39 and clamped thereto by the screw 46 with the plates reaching transversely to engage the hanger rod 36. A clamping bar 48 is mounted adjacent to the other end of the rod 39 and reaches transversely to support the vertical rod 49 which extends downwardly into the flyer socket 11 to the requisite depth. The rod 49 may be adjustably positioned by means of the locking

screw 50 which clamps the rod 49 and the clamping screw 51 which clamps the bar on the rod 39.

Spaced below the clamping bar 48 is another rod clamping bar 53 that is supported on the vertical rod 39 to retain the top rod member 54 which forms one section of the articulated rod which extends through the hollow leg of the flyer. Locking bolt and nut 56 clamp the rod 54 on the bar 53 and a screw 51 clamps the bar 53 to the vertical rod 39.

To facilitate the introduction of a rod through the hollow leg 17 of the flyer, the rod is articulated with the top member 54 and the bottom member 44 extending through the hollow leg member. These rod members 44 and 54 have their free ends machined to form a seating connection with the end of rod 54 having a conical end to engage with the countersunk end 56 of the lower rod end 44.

A copper plug 28 is introduced into the bottom open end of the socket of the flyer with the plug being tapered and slotted to form a resilient mounting to facilitate the mounting and removal of the flyer from the plug. The plug 28 is supported on the clamping bar 60 which reaches from the hanger rod 36 with the screw 61 tightening the bifurcated ends of the clamping bar about the periphery of the plug 28. The T-shaped handle 27 on the plug 26 will facilitate removal of the flyer from the plug upon completion of the plating operation by permitting a downward pull on the handle while the flyer is raised vertically from the plug.

Installation of the flyer frame 10 on the rack assembly 35 is facilitated by simply loosening the upper clamping bars 48 and 53 in order to displace the rods 49 and 54 vertically. Upon mounting of the flyer on the plug 26, the rods 49 and 54 are then lowered into position and the corresponding locking screws are tightened to retain the rods in the correct position in the flyer.

It has been found that the rods 44, 54 and 49 provide a very desirable means for directing the metallic ions into the internal surfaces to be plated so as to obtain a uniform flow of ions through the internal surfaces in order to produce the uniform depth of plate deposit.

It will be obvious to those skilled in this art that many modifications and improvements may be made to the rack assembly and fixture for supporting the flyer in order to obtain the requisite plating deposit at selective positions on the flyer as well as modifications made to the method of preparing the surface of the flyer, internally and externally, to obtain the requisite surface irregularity and roughness without departing from the real spirit and purpose of this inventive concept and many modifications are contemplated.

What is claimed is:

1. A flyer for textile spinning machines having a balancing leg, a hollow leg and an entrance socket having a rove opening therethrough, said flyer having a matte-finished chrome surface on external and internal portions of the balancing and hollow legs and the entrance socket to reduce fiber-to-metal friction and fiber choking.

2. A flyer for textile machines including roving frames, spinning frames and the like having a rove receiving socket with entrance and exit openings, a balancing leg, a hollow leg and a pressure foot mounted on said hollow leg, at least said hollow leg and socket having a matte-finished chrome surface throughout to reduce fiber-to-metal friction and fiber choking.

3. A flyer for textile machines including roving frames, spinning frames and the like having a rove receiving socket with entrance and exit openings, a balancing leg and a hollow leg, said hollow leg having a matte-finished chrome surface internally thereof to reduce fiber-to-metal friction and fiber choking.

4. A flyer for textile machines including roving frames, spinning frames and the like having a rove receiving socket with entrance and exit openings, a balancing leg, and a hollow leg, said hollow leg, balancing leg and

socket surfaces having a matte-finished chrome plate with a surface roughness in micro inches in the range of 75 to 200.

5. A flyer for textile machines for roving frames, spinning frames and the like having a rove receiving socket with entrance and exit openings, a balancing leg and a hollow leg, at least said hollow leg having a matte-finished chrome plate within the internal surface thereof and having a surface roughness in micro inches in the range of from 75 to 200.
